United States Patent

Des. 236,356
Patented Aug. 19, 1975

236,356

TELEPHONE INSTRUMENT

John Forrest Henshaw, Mill Valley, Victor Herbert Henshaw, Alamo, and Charles Phillips, San Francisco, Calif., assignors to Litton Business Telephone Systems, Inc., Sunnyvale, Calif.

Filed Dec. 18, 1974, Ser. No. 534,076

Term of patent 14 years

Int. Cl. D14—03

U.S. Cl. D26—14 A

Fig. 3

Fig. 4

Fig. 5

Fig. 6

Fig. 7

Fig. 8

Fig. 9

FIG. 1 is a front perspective view of a telephone instrument showing our new design;

FIG. 2 is a front perspective as seen from the side opposite of FIG. 1;

FIG. 3 is a front perspective view in an alternate position with the handset removed for clarity of illustration;

FIG. 4 is a top plan view thereof;

FIG. 5 is a front elevation thereof taken at a reduced scale;

FIG. 6 is a rear elevation thereof;

FIG. 7 is a right side elevation thereof;

FIG. 8 is a left side elevation thereof; and

FIG. 9 is a bottom plan view thereof.

We claim:

The ornamental design for a telephone instrument, as shown.
